UNITED STATES PATENT OFFICE.

HENRY G. ROTH, OF WHEELING, WEST VIRGINIA, ASSIGNOR TO OTT-HEISKELL COMPANY, OF WHEELING, WEST VIRGINIA, A CORPORATION OF WEST VIRGINIA.

POCKETKNIFE-DISPLAY CABINET.

Application filed November 20, 1922. Serial No. 601,969.

To all whom it may concern:

Be it known that I, HENRY G. ROTH, a citizen of the United States of America, and resident of Wheeling, county of Ohio, and State of West Virginia, have invented 5 certain new and useful Improvements in Pocketknife-Display Cabinets, of which the following is a specification.

This invention relates broadly to display 10 cabinets, and more specifically to a case or cabinet for displaying pocket knives.

The primary object of the invention is to provide a device of the character mentioned 15 which constitutes at once a case for containing a comparatively large stock of pocket knives and a cabinet for advantageously and attractively displaying such knives.

A further object is to provide a cabinet of the character referred to in which the 20 knives with blades open, or partially open, are displayed in such manner that customers may readily make selection therefrom without close examination or without objectionable touching or handling of the blades 25 which would result in the application thereto of moisture and in consequence of which tarnish or rust might follow.

In describing the invention in detail, reference is herein had to the accompanying 30 drawings, in which—

Figure 1 is a front elevation of the invention; and—

Figure 2 is a transverse horizontal section of the same.

Referring to said drawings, 1 indicates 35 a substantially upright casing, preferably of rectangular form in cross section, having a transparent glass front 2, preferably of hinged door form, said door permitting visual inspection of the contents of the casing 40 and affording convenient means of access to the interior of the casing when such is required.

Having their inner ends firmly mounted 45 in the rear wall 1^a of the casing and projecting horizontally forward into the interior of the latter are numerous slender posts or pins 3, preferably of escutcheon pin type, 50 designed to serve as supports for a plurality of pocket knives, herein shown in dotted lines and designated by the reference numeral 4. Said pins are arranged in pairs, each pair being adapted to support thereon one or more knives, the number of course 55 being dependent upon the sizes of the

knives and the length of the pins. The pins of each pair are spaced apart such a distance that, with the opposite end blades of knives half open, or disposed at right angles to the knife handles, they are 60 adapted to underlie the handles adjacent to the angles between said blades and said handles, this arrangement providing for the support of the knives in such manner that longitudinal shifting thereof to the extent 65 that they might become unbalanced is effectively prevented.

The pairs of pins are preferably arranged in a plurality of vertical rows, three such rows being shown in the drawing. Certain 70 of said rows, preferably the central row or rows, have the pins of each pair disposed in horizontal alignment providing for the support of knives in horizontal position, while others of said rows, as the opposite laterally 75 located rows, have the pins of the various pairs thereof disposed in parallel inclined planes, thus providing for the mounting of the knives in inclined parallel relation, as shown, with the uppermost pin of each pair 80 supporting the superposed knife or knives at the angle between the handles and half open blades of the latter.

It will be observed that the pins, arranged as described, provide mountings adapted for 85 supporting knives with their blades occupying open, or partially open, position in which visual examination thereof, without touching or handling, is facilitated; also, that the arrangement is such that the knives 90 are displayed in a particularly attractive manner.

A push pin 5 having a large button-like head upon which may appear the cost price or pattern number, or both, is provided below each of the various pairs of supporting pins 3.

A backing 6 consisting of a layer of suitable dark covering material, as green felt cloth, is preferably carried by the inner surface 100 of the rear casing wall 1^a.

What is claimed is—

1. A pocket-knife display cabinet comprising a substantially upright casing having a transparent glass door closing the front thereof, and pins mounted in the rear wall of said casing and projecting forward into the interior of the latter, said pins being arranged in pairs for supporting thereon one or more knives, the pins of each 110

pair being relatively spaced to underlie the knife handles adjacent to opposite ends of the latter, the pins of some of said pairs being disposed in horizontal planes and being adapted to engage the handles closely adjacent to the angles formed between said handles and the depending half-open opposite end blades, and the pins of others of said pairs being disposed in inclined planes in which the uppermost pin of each pair is adapted to engage a superposed knife in the angle between the handle and a depending half-open blade, and the lowermost pin underlies the opposite end of the handle.

15 2. A pocket-knife display cabinet comprising a substantially upright casing having a transparent glass door closing the front thereof, and pins mounted in the rear wall of said casing and projecting for-

ward into the interior of the latter, said pins being arranged for supporting thereon one or more knives, said pairs being further arranged in a plurality of vertical rows, the pairs of some of said rows having the pins thereof disposed in horizontal planes and spaced relatively to engage the overlying knife handles adjacent to the angles between said handles and depending half-open opposite end blades, and the pairs of others of said rows having the pins thereof disposed in inclined planes in which the uppermost pin of each pair supports the overlying knife at the angle between the handle and a depending half-open blade, and the lowermost pin underlies the handle at a point adjacent to its opposite end.

In testimony whereof, I affix my signature.

HENRY G. ROTH.
